FEELER-MOTION FOR LOOMS.

1,308,227.

Specification of Letters Patent.

Patented July 1, 1919.

Application filed April 7, 1916. Serial No. 89,715.

To all whom it may concern:

Be it known that I, FRANK B. DAVIS, a citizen of the United States, residing at Hopedale, in the county of Worcester and State of Massachusetts, have invented an Improvement in Feeler-Motions for Looms, of which the following description, in connection with the accompanying drawings, is a specification, like characters on the drawings representing like parts.

The invention to be hereinafter described relates to looms, and more particularly to the feeler motions thereof, whereby upon detection of substantial exhaustion of the filling in the running shuttle, a train of mechanism is rendered effective to change the operative condition of the loom, as by replenishing the supply of filling.

Various types of feeler motions have been devised, some of which have had a feeler to enter the shuttle on the detecting beat of the lay and by measuring the diameter of the filling in the shuttle have detected that condition of approaching exhaustion at which replenishment was desired and have thereupon initiated the replenishing operation. In other feeler motions, there have been penetrating and impinging feeler members, which, when the penetrating member has been struck by the surface of the filling carrier or bobbin, have initiated filling replenishment. In still another type, the feeler motion has been provided with a feeler, which, when the filling had reached substantial exhaustion, would be moved in a general direction longitudinally of the shuttle as the lay beat up, and by such movement would position an actuator for coöperation with a controller to effect filling replenishment on further forward movement of the feeler. In this type of feeler motion, the detecting member has been pivotally offset upon its carrier and provided with a filling engaging end, such that, while a working supply of filling was present on a detecting beat, the detecting member would be held from movement on its pivot relative to the bobbin by the mass of filling thereon, but when the filling had become substantially exhausted, and while sufficient still remained in the shuttle to reach several times across the lay, the forward push of

the bobbin would turn the detecting member upon its pivot and thereby swing the actuator into position to operate the controller as the feeler was moved farther to the front of the loom, and thereby initiate replenishment of the filling. As well understood by those skilled in the art, a feeler motion must be sensitive and reliable in the discharge of its detecting function in order that it will not call for a change when a working supply of filling is present in the shuttle, and yet effect replenishment when substantial exhaustion is reached. It must be light, also, and easily moved by the forward push in order that no injury shall be done the filling during the recurrent engagements therewith during weaving, and especially should it not pick under the final layer or layers of filling when substantial exhaustion is reached, which would tend to prevent the forward push of the bobbin from moving the feeler member into position for the discharge of its detecting function or break the filling itself.

An important feature of the present invention, therefore, consists of a feeler motion wherein the filling feeler or engaging member shall be mounted upon its carrier so that upon substantial exhaustion of the filling the feeler member shall be moved bodily longitudinally of the shuttle by the forward push upon the feeler member. In the present instance of the invention, this character of bodily movement is effected by mounting the filling engaging member of the feeler upon its carrier by parallel motion devices, which may take various forms, as for instance, parallel link connections, in which case the feeler member will be prevented from angular movement relative to the bobbin in the shuttle and consequently its engaging end will not pick under or pass between the coils of yarn and the bobbin and tend to break the yarn or be held from its detecting movement.

The above and other features of the invention will be hereinafter described in connection with the accompanying drawing and then definitely set forth in the claims.

In the drawings:—

Figure 1 is a plan view of a feeler motion embodying features of the present inven-

tion, only sufficient of the loom parts being illustrated as are necessary to make clear the association of the present invention therewith;

- 5 Fig. 2 is a section on the line 2—2, Fig. 1;
Fig. 3 is a plan view showing the action of the feeler on the detecting beat-up movement of the lay when a working supply of filling is present in the shuttle; and
10 Fig. 4 is a similar view showing the position of parts on a detecting beat when the filling is substantially exhausted.

The feeler motion, in the present invention, comprises a feeler carrier which is mounted on a fixed portion of the loom or a bracket secured thereto for movement toward and from the front of the loom and mounted upon the feeler carrier is the feeler member which directly receives the forward push of the filling mass in the shuttle as the lay beats up. This feeler member has a roughened or toothed portion which, when a working supply of filling is present, engages the mass of filling on the detecting beat and is held from bodily movement relative to the feeler carrier by the filling; but when the filling has become substantially exhausted and only sufficient remains upon the bobbin in the shuttle to extend one or more times across the lay, the toothed portion of the feeler member will engage the surface of the bobbin and be no longer restrained from bodily movement longitudinally of the shuttle by the forward push of the bobbin against it, but will move bodily in such direction under the forward impulse of the bobbin and thereby position an actuator operatively with respect to a controller so that on movement of the filling carrier 10 while the filling member is thus displaced bodily with respect thereto, the actuator will move the controller and initiate filling replenishment. In the present instance the feeler motion comprises a casing or stand 1 which may be appropriately secured to the loom frame or bracket secured thereto by means of suitable screws 2 or other fastening devices. Mounted in the casing or stand 1 is the feeler carrier which is capable of movement toward and from the front of the loom. In the present instance, the feeler carrier comprises a plate 3 having a shank or front portion 4 and supported for reciprocating movement in the stand 1. The feeler carrier 3 is normally under the influence of a spring which maintains the feeler carrier in its projected rear position, substantially as indicated in Fig. 1. In the present instance, the shank or stem 4 of the feeler carrier 3 is surrounded by a spring 5 one end of which bears against a shoulder 6 of the feeler carrier, and the other end against the inner surface 7 of the stand 1, the construction being such that by forward pressure the

feeler carrier 3 may be moved forwardly 65 against the action of the spring 5 and when such forward pressure is removed, the spring 5 may return the feeler carrier 3 to its normal or feeling position.

The feeler carrier 3 has mounted thereon 70 a feeler member which directly receives upon it the forward push of the filling in the shuttle on the detecting beat, and such feeler member is connected to the feeler carrier so that when the filling becomes substantially 75 exhausted and the time arrives at which a replenishment of the filling is desirable, such feeler member will be moved bodily in a direction longitudinally of the shuttle by the forward push exerted thereupon as the lay 80 makes its detecting beat, and thereafter both the feeler member and the feeler carrier will be moved forward to cause the actuator controlled by the feeler member to engage the controller and initiate filling replenish- 85 ment.

In the present instance of the invention, the feeler member is connected to the feeler carrier by parallel motion devices such that when displaced longitudinally of the shuttle 90 by the forward push exerted upon it, such feeler member will be prevented from changing its angular relation with the longitudinal axis of the bobbin, and the teeth or engaging portion of the feeler member will not 95 pick under the coils of filling still remaining on the bobbin as it performs its detecting movement.

In the illustrated form of the invention, the feeler member comprises a feeler portion 8 provided with a series of teeth or roughened portions 9 which are adapted to engage either the mass of filling in the shuttle and be held thereby from longitudinal movement relative to the shuttle when a 105 working supply of filling is present on a detecting beat, but which, when the filling has become substantially exhausted, will move longitudinally along the surface of the bobbin under the forward push thereof, without changing the angular relation of the feeler member with respect to the longitudinal axis of the bobbin or the feeler carrier. To effect this bodily longitudinal movement of the feeler member under the conditions 110 stated, said feeler member is connected to the feeler carrier by parallel motion devices shown in the present instance as comprising the two links 10 and 11, one end of each link being pivotally connected at 12 to the feeler 115 member and the other end connected at 13 to the feeler carrier. Interposed between the feeler member and the feeler carrier 3 is a light spring 14, which normally maintains the feeler member projected rearwardly 120 beyond the end of the feeler carrier, but permits such feeler member to move toward the feeler carrier under the frontward im-

pulse of the bobbin when the filling has become substantially exhausted.

As a convenient and good practical form of the parallel motion connection between the feeler member and the feeler carrier, said feeler member may be provided with a slotted portion 15 as indicated by dotted lines in Figs. 1, 2 and 3; and likewise, the end of the feeler carrier 3 may similarly be provided with a slotted portion 16, the edge of said slotted portions being adapted for the reception and movement between them of the parallel links 10 and 11. Owing to the stress upward or downward that may sometimes be exerted upon the feeler member on the forward impulse of the bobbin or the filling thereon, the slotted end portion 16 of the feeler carrier 3 is made sufficient in dimension to permit sliding movement of the feeler member therein, substantially as indicated in Fig. 2.

Operatively connected to the feeler member is an actuator which, in the present instance, comprises an arm 17 extending from the feeler member frontwardly along the side of the feeler carrier 3, the construction being such that when the feeler member is in its normal feeling position as indicated in Fig. 1, the actuator 17 will engage the side of the feeler carrier 3 and constitute a stop to limit the projecting movement of the feeler member beyond the end of the feeler carrier under the impulse of the spring 14, substantially as indicated in Figs. 1 and 3. The spring for projecting the feeler member beyond the end of the feeler carrier into its normal position may be variously applied, but in the present instance it is conveniently placed between the parallel motion devices connecting the feeler member and the feeler carrier. In order that the feeler member and actuator operatively connected thereto shall be properly guided as the feeler member is moved bodily longitudinally of the shuttle on a detecting beat when the supply of filling has become substantially exhausted, the feeler 3 is preferably provided with an enlarged head 18 for the accommodation of the slot or opening 16, and such slot or opening 16 may be continued along the side of the feeler head for the reception of the actuator 17 as the feeler member and said actuator are bodily moved by the forward push of the bobbin when the filling is substantially exhausted.

As usual in this character of loom, the shuttle-box 19 is provided with an opening 20 in its front wall and similarly, the wall 21 of the shuttle 22 is provided with an opening 23, so that the feeler member may enter the shuttle and detect the condition of the filling therein on the detecting beat. The bobbin 24 may be of usual construction and maintained in position in the

shuttle for delivery of the yarn during the weaving operation by suitable means such as the usual jaws 25 and the jaw engaging rings 26.

The present invention contemplates that when the filling has become substantially exhausted on a detecting beat, the feeler member may be moved bodily in a direction longitudinally of the shuttle without changing its angular relation to the axis of the bobbin so that the engaging teeth or roughened portions of the feeler member shall not pass between the surface of the bobbin and the coils of yarn thereon, which would have a tendency to break the filling or destroy the sensitiveness of the detecting action of the feeler member. When the feeler member has been thus moved, the actuator 17 is positioned for engagement with a controller 27 as the feeler carrier 3 is moved frontwardly during the beatup movement. The controller 27 may be variously formed and connected to any desired train of mechanism for changing the operative condition of the loom and in the present instance it is of the general character now well known for initiating filling replenishment. In order that the controller 27 may be properly guided as it is moved by the actuator from the position indicated in Figs. 1 and 3 to that indicated in Fig. 4, said controller is preferably directed in its movement by a guide 28 which may take the form of a bracket or arm projecting from the feeler stand 1. In the present instance of the invention, this guide or bracket 28 may be secured to the feeler stand by suitable means such as the screws 29.

From the construction described as a good practical form of the present invention, it will be noted that when a working supply of filling is present in the shuttle on a detecting beat, the mass of filling will engage the teeth 9 of the feeler member and will prevent bodily movement of the feeler member longitudinally of the shuttle as the lay completes its forward movement, the feeler member and feeler slide being moved bodily to the front, substantially as indicated in Fig. 3. When, however, the filling in the shuttle has become substantially exhausted as indicated in Fig. 4, the amount of filling on the bobbin will no longer be sufficient to prevent movement of the feeler member longitudinally of the shuttle under the forward impulse or push exerted against the feeler member, and said feeler member will thereupon bodily move under the direction of the parallel motion devices while maintaining its unchanged angular relation to the axis of the shuttle or the bobbin therein, substantially as indicated in Fig. 4. When the feeler member has thus been bodily displaced longitudinally of the shuttle, the actuator 17 will be positioned operatively

with relation to the controller 27 and upon farther forward movement of the feeler member and feeler carrier 3 said controller 27 will be moved to initiate filling replenishment or otherwise act through a train of mechanism to change the operative condition of the loom. When the feeler member has been thus bodily displaced longitudinally of the shuttle, it will have compressed the spring 14 and the edge portion 31 of the feeler carrier will constitute a stop for limiting the longitudinal displacing movement of the feeler member by engagement with the edge portion 30 of the feeler member.

15 What is claimed is:—

1. A feeler motion for looms, comprising a feeler member to directly engage the filling in the shuttle on a detecting beat and bodily 20 displaced longitudinally of the shuttle by the forward pressure when the filling is substantially exhausted, an actuator combined with said feeler member having a reciprocating stroke, a controller adapted to 25 be moved by the actuator in its normally-directed stroke when the feeler member has been bodily displaced longitudinally, and means for preserving the angular relation of the shuttle and feeler member unchanged 30 as the feeler member is bodily displaced longitudinally of the shuttle by the forward push.

2. In a feeler motion for looms, the combination of a feeler carrier, a feeler member, 35 connections between the feeler member and feeler carrier for confining the feeler member to parallel movements as it is displaced longitudinally of the shuttle by the forward pressure of a surface within the shuttle 40 when the filling is substantially exhausted, an actuator connected to the feeler member for movement toward the front of the loom, and a controller normally out of the path of the actuator as it is moved forward 45 wardly and adapted to be operated by the actuator when the feeler member has been displaced longitudinally of the shuttle by the forward pressure.

3. In a feeler motion for looms, the combination of a feeler member that receives the 50 push of the filling contained in the shuttle and is bodily displaced longitudinally of the shuttle by the forward pressure when the filling is substantially exhausted, means 55 acting as the feeler member is bodily displaced longitudinally of the shuttle by the forward pressure to prevent angular movement of the engaging portion of the feeler and cause it to travel along the bobbin in unaltered angular relation to the axis thereof, an actuator having a normally directed reciprocating stroke and operatively positioned by the bodily lateral displacement of the feeler member, and a controller that is 60 actuated by the normally directed stroke of 65

the actuator toward the front of the loom when operatively positioned by the laterally displaced feeler member.

4. A feeler motion for looms comprising a feeler carrier, a feeler for engaging the filling in the shuttle, parallel link motion devices connecting the feeler with the feeler carrier for movement bodily toward the feeler carrier and in a direction longitudinally of the shuttle when the filling is substantially exhausted on a detecting beat, means for normally holding the feeler carrier in rearward position and permitting it to yield forwardly, an actuator movable with the feeler carrier as the latter moved 75 forwardly, and a controller adapted to be actuated by forward movement of the actuator when it has been laterally displaced.

5. In a feeler motion for looms, a feeler carrier, a feeler member, parallel motion devices connecting the feeler carrier and feeler member for directing the lateral movement of the feeler member in a direction to preserve the parallel relation of said feeler member and bobbin in the shuttle when the 80 feeler member is laterally displaced by the forward push against it, an actuator connected to and bodily movable with and in the same direction as the feeler member, and a controller adapted to be actuated by the 85 feeler member when the feeler member has been laterally displaced.

6. In a feeler motion for looms, the combination of a feeler carrier mounted for reciprocating movement toward and from the 100 front of the loom, a feeler member for directly receiving the push of the filling in the shuttle as the lay beats up and bodily displaced longitudinally of the shuttle by the forward push of a surface carried by the 105 shuttle when the filling is substantially exhausted, parallel motion connections between the carrier and feeler member for preventing relative angular movement of said parts when the feeler member is displaced longitudinally of the shuttle, an actuator adapted 110 to be moved by and in the same direction as the feeler member, and a controller operated by the actuator.

7. In a feeler motion for looms, the combination of a feeler member movable in a direction longitudinally of the shuttle by the forward pressure of a surface within the shuttle when the filling is substantially exhausted on a detecting beat, means for confining the feeler member to parallel movements longitudinally of the shuttle, an actuator having a normally directed stroke toward the front of the loom, and a controller adapted to be operated by the actuator.

8. In a feeler motion for looms, the combination of a feeler member having a toothed engaging edge portion to receive the forward push of the filling mass as the lay beats up and to be displaced longitudinally 130

of the shuttle by the forward push of the bobbin when the filling is substantially exhausted, a feeler carrier, guiding means between the feeler carrier and feeler member 5 to cause the toothed portion of the feeler member to maintain its angular relation to the axis of the bobbin unchanged and in parallel paths as it is moved longitudinally of the bobbin, a controller, and an actuator 10 moved into operative relation with the controller by longitudinal displacement of the feeler member.

9. In a feeler motion for looms, the combination of a feeler carrier, a feeler member, 15 parallel links connecting the feeler member to said carrier, a spring normally acting to project the feeler member beyond the end of the carrier and yielding to permit bodily movement of the feeler member laterally of 20 the feeler carrier by the forward push of the bobbin when the filling is substantially exhausted on a detecting beat of the lay, an actuator bodily movable with and in the same direction as the feeler member, and 25 means operated by the actuator when the feeler member is displaced laterally on a detecting beat to initiate filling replenishment.

10. In a feeler motion for looms, the combination of a feeler carrier, a feeler member 30 projecting beyond the end of the carrier and having a toothed portion to receive the push of the filling in the shuttle as the lay beats up and to be bodily displaced longitudinally of the shuttle by the forward push upon it 35 when the filling is substantially exhausted, parallel motion devices connecting the feeler member and feeler carrier to cause such bodily movement of the feeler member to be made while maintaining unchanged the 40 angular relation of the feeler carrier and feeler member, yielding means acting to move the feeler member bodily in the opposite direction when relieved of the forward push upon it, means for limiting relative movement of the feeler carrier and 45 feeler member in either direction, an actuator

bodily movable with and in the same direction as the feeler member to initiate filling replenishment upon frontward movement of the feeler carrier when the feeler member has been laterally displaced. 50

11. In a feeler motion for looms, the combination of a feeler carrier, a feeler member projecting beyond the end of the carrier and having a toothed portion to receive the 55 push of the filling in the shuttle as the lay beats up and to be bodily displaced longitudinally of the shuttle by the forward push upon it when the filling is substantially exhausted, parallel motion devices pivotally 60 connecting the feeler member and feeler carrier at points separated longitudinally of the shuttle to cause such bodily movement of the feeler member to be made while maintaining unchanged the angular relation of 65 the feeler carrier and feeler member, yielding means acting to move the feeler member bodily in the opposite direction when relieved by the forward push upon it, a controller, an actuator operatively positioned 70 with respect thereto by the bodily lateral movement of the feeler member due to the forward push, and stops to limit the bodily movement of the feeler member in each direction. 75

12. A feeler motion for looms, comprising a feeler carrier mounted for movement toward and from the front of the loom, a feeler member mounted on the feeler carrier and bodily movable in parallel paths longitudinally of the shuttle by the forward push of the bobbin when the filling is substantially exhausted, an actuator operatively connected to and bodily movable in the same direction as the feeler member, and a controller adapted to be actuated by the actuator when the feeler member has been moved longitudinally of the shuttle by the frontward push. 80

In testimony whereof, I have signed my 90 name to this specification.

FRANK B. DAVIS.
